DETACHABLE AND ADJUSTABLE CAP FOR GARMENTS

Nathan Frankel, Brooklyn, N. Y.

Application July 11, 1935, Serial No. 30,779

1 Claim. (Cl. 2-84)

This invention relates to new and useful improvements in a detachable and adjustable cap for garments.

The invention has for an object the association 5 of a cap with a lumber jacket, windbreaker, coat and the like in a fashion characterized by the fact that the collar portion of the coat is connected with the back of the cap.

Still further the invention particularly 10 proposes the provision of a slide fastener for connecting these adjacent parts together.

Another one of the objects of this invention is the arrangement of several lines of slide fastener elements upon the cap so that it may be attached 15 at various levels to control its operative size.

Still further, in order to better control the size 20 of the cap it is proposed to arrange the cap with an opening extended in from one edge thereof which may be closed to various degrees by the provision of a slide fastener thereon.

Another object of the invention is the construction 25 of an article as described which is simple and durable and which may be manufactured and sold at a reasonable cost.

For further comprehension of the invention, and of the objects and advantages thereof, reference will be had to the following description and accompanying drawing, and to the appended 30 claim in which the various novel features of the invention are more particularly set forth.

In the accompanying drawing forming a material part of this disclosure:—

Fig. 1 is a front elevational view of a garment 35 with a detachable and adjustable cap constructed according to this invention.

Fig. 2 is an elevational view of the inner side 40 of the cap after it has been detached from the garment.

Fig. 3 is a side elevational view of Fig. 1.

Fig. 4 is a fragmentary enlarged sectional view 45 taken on the line 4—4 of Fig. 3.

Fig. 5 is a fragmentary elevational view looking in the direction of the line 5—5 of Fig. 3.

Fig. 6 is a perspective view of a different type 50 of separable garment and cap which may be worn separately when the detachable cap is removed.

Fig. 7 is a front elevational view of the cap 55 illustrated in Fig. 6, removed from the garment.

Fig. 8 is a perspective view of the garment illustrated in Fig. 6, with the cap removed.

The detachable and adjustable cap for garments, according to this invention, is associated with a garment 10 which has a collar portion 11. The cap 12 has its back edge 12' extending

along the collar portion 11. A line of slide fastener elements 13 are mounted upon the collar portion and is adapted to cooperate with a line of complementary slide fastener elements 13' mounted upon the back edge of the cap. A control slide 14 is associated with the slide fastener elements in such a manner that when drawn in one direction the elements are engaged, and when drawn in the other direction they are disengaged.

The cap 12 is formed with an opening 16 extended in from one side thereof, preferably the front side, and extending to the top center of the cap. This opening is equipped with a slide fastener 17 so that it may be opened and closed as desired. It is proposed to open the slide fastener 17 to any desired degree to loosen or open the cap when worn.

The garment 10 is shown with a front opening 18 which is closeable by a slide fastener 19. The slide fasteners 13 and 13' are arranged so that the elements thereof may be completely disengaged so that the cap is removable when desired.

This is accomplished by constructing the end of the line of slide fastener elements 13 with an enlarged portion 13^a so that the control slide 14 cannot become displaced therefrom. The corresponding end of the line of slide fasteners 13' is formed with a stud element 13^b adapted to be drawn out from its co-action with the element 13^a when the slide fastener is completely open. This permits the free removal of the cap and its replacement when desired.

Another line of slide fastener elements 20 is mounted upon the lining of the cap 12 spaced in from the back edge thereof so as to be parallel 35 with the line of fasteners 13'. The slide fastener elements 20 terminate at one end in a stud element 13^b which is adapted to cooperate with the element 13^a to permit the control slide 14 to attach the slide fastener elements together. Thus,

if the cap is attached with the slide fastener elements 13 in such a manner that the slide fastener elements 20 are connected with the slide fastener elements 13, then the cap is mounted relatively lower down on the garment. Thus, it is possible 40 to adjust the cap to several different positions.

Additional lines of fastener elements may be used if desired to increase the degree of adjustment. Attaching the cap by its lining to the garment also distributes the strain of the attaching so 45 that relatively few wrinkles result, and those wrinkles which do occur are in the lining rather than on the outside of the cap.

In Figs. 6 and 7, a cap 25 is illustrated which 50 may be substituted for the cap 12 when the latter

- cap is removed. This cap 25 is a standard cap without the front slide fastener 17. The cap is provided with snap fastener members 26 at the inner side for the purpose of engaging corresponding snap fastener members 27 of the conventional ear muffs 28'. The ear muffs are joined with elastic bands 29 which may be placed under the chin or within the cap as illustrated in dot and dash lines.
- 10 The style of the garment 10' shown in Figs. 6 and 8, is different from that illustrated in Fig. 1, but both the style of the garment as well as of the cap may be changed as desired and may be of any suitable material.
- 15 While I have illustrated and described the preferred embodiment of my invention, it is to be understood that I do not limit myself to the precise construction herein disclosed and the

right is reserved to all changes and modifications coming within the scope of the invention as defined in the appended claim.

Having thus described my invention, what I claim as new, and desire to secure by United States Letters Patent is:—

A detachable cap for garments having inner and outer plies, said inner ply comprising a lining for said cap, said lining having a row of fastening elements thereon, said garment having means 10 cooperating with said fastening elements for attaching said cap to said garment, said row of fastening elements being substantially set back from the lower edge of said cap and directly supported only by said lining whereby said cap is 15 held to said garment by the lining of said cap.

NATHAN FRANKEL.
